UNITED STATES PATENT OFFICE.

ALBERT LEONARD, OF DULUTH, MINNESOTA, ASSIGNOR OF ONE-HALF TO AXEL EDMAN, OF DULUTH, MINNESOTA.

COMBINATION-LOCK.

1,146,720.

Specification of Letters Patent. Patented July 13, 1915.

Application filed December 8, 1913. Serial No. 805,384.

To all whom it may concern:

Be it known that I, ALBERT LEONARD, a citizen of the United States, residing at Duluth, in the county of St. Louis and State 5 of Minnesota, have invented certain new and useful Improvements in Combination-Locks, of which the following is a specification, reference being had therein to the accompanying drawing.

10 My invention relates to improvements in combination locks the primary object of which is to construct a combination or permutation lock which will occupy a minimum of space.

15 A further object of the present improvement is to so construct the lock that it is of the greatest simplicity of construction and hence economy of manufacture.

Another object of the present improvement 20 is to provide a combination lock which is automatically released when the combination has been set.

In the accompanying drawings—Figure 1 is a side elevation of the locking device with 25 all the tumblers removed except the first. Fig. 2 is an enlarged cross sectional view of the tumblers and showing the arranged relation of one to the other. Fig. 3 is a view of the last tumbler and also showing its 30 means of engagement with the next adjacent tumbler. Fig. 4 is a side elevation of the tumbler knob by means of which the lock is operated. Fig. 5 is a side elevation of the shaft which forms the connection between 35 the tumbler knob and the tumblers. Fig. 6 is a side elevation of a thumb shaft by means of which the tumbler shaft is connected to the tumbler knob. Fig. 7 is an 40 end elevation of the entire mechanism assembled and in position on the door. Fig. 8 is a front elevation of Fig. 7.

Referring now to the drawing in which like reference numerals designate similar parts, 1 represents the case which is of a 45 rectangular form and is adapted to receive the various parts of the locking mechanism. Within the case 1 are arranged a plurality of tumblers 2, 3 and 4. The tumbler 2 has an unbroken surface adjacent the back wall 50 of the containing case 1 and on the opposite side thereof is a cut-in annular groove 6, the outer edge of which is circular in form and the inner edge thereof is established by the polygonal center 7 of the tumbler and

through this center a circular hole 8 is provided for the admission of a tumbler shaft 9. The tumblers 2, 3 and 4 are of the same size and shape except in respect to the circular hole 8 through their centers. The hole 8 in the tumblers 2 and 3 is of the same size 60 and of considerably greater cross section than the thickness of the tumbler shaft 9. The hole 8 in the tumbler 4 is of a size and shape to exactly fit the end of the tumbler shaft 9 as is readily understood. Within 65 the groove 6 in the tumbler 2 is provided a removably and adjustably fitted ring 10 which is in turn provided with an annular groove 11 within which at a suitable point is a stop 12. The tumbler 3 is also provided 70 with a removably and adjustably fitted ring 10 provided with a groove 6 and a lug 13 upon the surface thereof adjacent that of the tumbler 2, and the said lug 13 will fall within the annular groove 11 on the tumbler 75 2 and be revolved about in the said groove by the motion of the tumbler, of which it is an integral part, until it comes in contact with the stop 12 of the preceding tumbler, thus setting in motion the preceding tum- 80 bler, and moving it to the desired position. A lug 13 is also provided on the tumbler 4 which acts similarly upon the intermediate tumbler 3, both of the tumblers 3 and 2 de- 85 riving their motion from the tumbler 4 as will be more fully pointed out hereinafter.

It is well understood that any number of tumblers may be employed in order to complicate the combination feature of the locking device without departing from the spirit 90 and intent of this invention. In the last tumbler 4, the groove 6 and ring 10 are dis- 95 pensed with, but this tumbler is provided with a lug 13 for engagement with the stop 12 of the next preceding tumbler 3. Each tumbler, though circular in shape, has a chord removed from one edge, each in a like manner, resulting in a flattened side or edge as is clearly shown. There is also provided a spring or springs 14 for each tumbler and 100 these springs are connected to the inside of the case 1. They are adapted to engage each tumbler separately and to maintain a constant pressure thereupon in a direction toward the locking device and to hold the 105 tumbler stationary and to keep it from being moved as each succeeding tumbler is set. The locking device consists of a rectangular

bar or plate 15 which is superimposed against the edges of the tumblers and exerts a pressure upon them by means of the spiral springs 16-16 which are here shown to be engaged about the bolts 17-17 which are disposed at right angles to the bar 15 and which project through corresponding holes in the case 1 and are designed to engage with the door frame in such a manner as to fit within suitable orifices made therewithin as is readily understood.

A dial is arranged upon a bearing plate 18 which is an integral part of the tumbler knob 19 and by means of which the possessor of the combination may release or set the lock. The tumbler shaft 9 is designed to pass through a hole in the back of the case 1, opposite the hole in the last tumbler as herein before stated, through the hole in the last tumbler 4, through the circular holes in the tumblers 2 and 3, through the front side of the case 1, and into a corresponding orifice within the tumbler knob 19 as indicated in Fig. 4. A thumb screw shaft 21 is also provided which is designed to pass longitudinally through a hole in the center of the shaft 9 and thence into a threaded orifice 22 within the tumbler knob 19 thus uniting the various parts of the lock.

In operation the tumbler 2, is first set with its flattened portion against the bar 15, and this is done by turning the knob 19 which revolves the last tumbler 4 to which it is connected by means of the tumbler shaft 9. As the tumbler 4 is revolved, through the medium of the lugs 13 and stops 12 on the tumblers 2 and 3, it carries these tumblers with it and consequently the possessor of the combination revolves the dial the necessary number of times to bring the tumbler 2 in position. The spring 14 then holds this tumbler in the position in which it is left and the dial is then turned in the opposite direction. In like manner after a correct number of turns the tumbler 3 is placed in position with its flattened portion opposite the plate 15. The dial is then again revolved in the opposite direction and the tumbler 4 is set with its flattened portion against the bar 15 and as soon as it is placed in this position, the flattened portions of all the tumblers registering, the plate 15 is forced inward by the springs 16-16 thereby drawing the bolts 17-17 out of engagement with the door frame.

As has been pointed out the inmost tumbler 4 is the only one which is revolved directly by the shaft 9 as the hole therein is of the same polygonal shape as that of the shaft and the other tumblers are only revolved as the lug 13 on the one impinges the stop 12 on the other. Thus the stop 12, which is an integral part of the ring 10, in any one of the tumblers is set so that when impinged by the dog of the preceding tum-

bler that the flattened side or chord of the tumblers do not register, then no amount of turning of the tumbler knob in either direction continuously will ever effect an unbolting of the lock.

70

The possible adjustment of the rings 10 within the grooves 6 in the tumblers may be varied by varying the number of sides of the polygonal centers of the tumblers, thus providing a greater multiplicity of relative positions for the stops 12 in each tumbler and thus increase the possible combinations of the lock. The shaft 9 may be correspondingly changed in its cross sectional shape to allow of such variation, and it is clearly evident that any change of position of this shaft 9 either in relation to the tumbler 4 or the tumbler knob will alter the combination.

80

Having thus fully described my invention what I claim and desire to secure by Letters Patent is:

1. In a permutation lock, a housing, a polygonal shaft mounted within the housing, a plurality of tumblers mounted upon the shaft within the housing, one of the tumblers having a polygonal opening interlocking with the polygonal shaft, grooves in the upper faces of the tumblers having polygonal edges at their centers, removable rings in the said grooves and having polygonal inner edges, the said rings having a groove in their upper face, and a lug in the said groove, lugs on the lower faces of the tumblers adapted to engage the said lugs in the removable rings, whereby the combination of the lock may be altered by removing the rings and placing their polygonal edges opposite different polygonal edges of the grooves.

95

2. A combination lock comprising a housing, a polygonal shaft therewithin, a plurality of tumblers mounted on the said shaft, grooves in the upper faces of the tumblers having polygonal edges at their centers, removable rings in the said grooves having polygonal edges at their centers, the said rings carrying connecting means between the tumblers, said means comprising a circular groove in the removable ring, and a lug therewithin, and a lug on the lower face of the tumbler to engage the first-mentioned lug.

100

3. In a permutation lock, a housing, a polygonal shaft mounted within the housing, a plurality of tumblers mounted upon the shaft within the housing, one of the tumblers having a polygonal opening interlocking with the polygonal shaft, circular grooves in the upper faces of the tumblers having polygonal edges at their centers, removable circular rings fitting within the said grooves and having polygonal inner edges, whereby the combination of the lock may be altered by removing the rings and placing their edges opposite different polyg-

120

125

130

onal edges of the grooves and by changing the interlocking connection between one of the tumblers and the polygonal shaft, circular grooves formed in the upper surface of 5 the removable rings, and a lug formed in the said groove, a projection carried by the lower faces of the tumblers and running in the said grooves, said lug adapted to engage

the lug fastened in the groove, the parts arranged as and for the purpose described. 10

In testimony whereof I hereunto affix my signature in the presence of two witnesses.

ALBERT LEONARD.
